PATTERN TRACER

Ernest J. Camos, 9078 Villaridge Court,
St. Louis, Mo. 63123

Filed May 27, 1969, Ser. No. 17,385

Term of patent 14 years

Int. Cl. D6—99

U.S. Cl. D3—19

FIG. 1

FIG. 2

FIG. 3

FIG. 4

FIG. 5

FIG. 1 is a side perspective view of a pattern tracer, showing my new design;

FIG. 2 is a side elevational view of the side opposite thereto;

FIG. 3 is a top plan view;

FIG. 4 is an end elevational view; and

FIG. 5 is a sectional view taken along line 5—5 of FIG. 2.

I claim:

The ornamental design for a pattern tracer, substantially as shown.
